UNITED STATES PATENT OFFICE.

WILLIAM CHESTER PHELPS, OF NEW YORK, N. Y., ASSIGNOR TO S. M. BIXBY & CO., OF SAME PLACE.

MUCILAGE-BRUSH SCRAPER.

SPECIFICATION forming part of Letters Patent No. 433,090, dated July 29, 1890.

Application filed March 16, 1890. Serial No. 343,977. (No model.)

To all whom it may concern:

Be it known that I, WILLIAM CHESTER PHELPS, a citizen of the United States, residing in the city and county of New York, § and State of New York, have invented new and useful Improvements in Brush-Scrapers for Mucilage and other Bottles, of which the following is a specification.

The object of my invention is to provide a detachable brush-scraper placed at the base of the throat of mucilage, glue, or other bottles, whereby to clean the brush of superfluous gum at a point where it will not fill up the mouth of the bottle.

The device may be attached to any ordinary short-necked bottle, and is held in position in the manner hereinafter described.

The device, as shown by the accompanying drawings, to which reference is made, consists of a wire or piece of metal, shaped like a figure 2, the lower or horizontal bar of which extends across the diameter of the throat of the bottle and forms the brush-scraper.

In the drawings, Figure 1 represents the brush-scraper when placed in position in the bottle for use, and Fig. 2 shows the same when detached.

The end of the wire from *a* to *b*, which serves to clean the brush, engages or bears against the interior roof of the bottle, passes ³⁰ up through the throat of the neck, and is hooked over the mouth and down the side to *c*, forming a pressure-spring which holds it firmly in position. The wire or metal which passes through the throat of the neck is flattened or shaped so as to avoid interference with the cork, which may be the more readily inserted after the device has been placed in position.

I claim—

As a new article of manufacture, a brush-scraper adapted to be secured to a bottle by being sprung thereon and consisting of a hook *c*, flattened along the interior of the throat of the bottle and terminating in a horizontal bar *a b*, extending across the diameter of the throat of the bottle and resting against the inner roof of the same, substantially as described.

WILLIAM CHESTER PHELPS.
